H. L. MacCOWAN

Des. 126,368

COMBINED BAROMETER AND THERMOMETER

Filed July 1, 1940

INVENTOR.

Hervey L. MacCowan

UNITED STATES PATENT OFFICE

126,368

DESIGN FOR A COMBINED BAROMETER AND THERMOMETER

Hervey L. MacCowan, Wilmette, Ill., assignor to Fee and Stemwedel, Inc., Chicago, Ill.

Application July 1, 1940, Serial No. 93,367

Term of patent 7 years

to all whom it may concern:

Be it known that I, Hervey L. MacCowan, a citizen of the United States, residing at 1431 Forest Avenue, in the village of Wilmette, in the county of Cook and State of Illinois, have invented a new, original, and ornamental Design for a Combined Barometer and Thermometer, of which the following is a specification, reference being had to the accompanying drawing, forming part thereof.

The figure is a perspective view of a combined barometer and thermometer showing my new design.

I claim:

The ornamental design for a combined barometer and thermometer, as shown.

HERVEY L. MACCOWAN.
